UNITED STATES PATENT OFFICE.

NAPOLÉON BOISVERT, OF SALMON FALLS, NEW HAMPSHIRE, ASSIGNOR OF THREE-FOURTHS TO JAMES HAMILTON AND HERBERT E. HAMILTON, BOTH OF SAME PLACE, AND EDWARD M. BALL, OF GREAT FALLS, NEW HAMPSHIRE.

SHUTTLE-CHECK FOR LOOMS.

SPECIFICATION forming part of Letters Patent No. 405,980, dated June 25, 1889.

Application filed March 23, 1889. Serial No. 304,490. (No model.)

To all whom it may concern:

Be it known that I, NAPOLÉON BOISVERT, a citizen of the United States, and a resident of Salmon Falls, in the county of Strafford and State of New Hampshire, have invented certain new and useful Improvements in Shuttle-Checks for Looms; and I do hereby declare the following to be a full, clear, and exact description of the invention, such as will enable others skilled in the art to which it appertains to make and use the same.

My invention relates to improvements in shuttle-checks for looms; and it has for its object to simplify and cheapen the intermediate connections between the swell of the shuttle-box and the pitman that connects the lay and crank-shaft, whereby the swell is released from the shuttle when the latter leaves its box to insure a smooth easy movement to the shuttle, which relieves all undue strain on the filling as well as on the pick-motion and picker-staff, and causes less breakage of the warp-threads.

With these ends in view my invention consists in the combination, with a pitman intermediate of the lay and crank-shaft, a rock-shaft carrying a binder arm or finger, a swell, and a spring connected to said rock-shaft, of a vertically-reciprocating rod connected at its lower end to said spring and bent laterally of the lay-sword on which it is guided, said rod being connected at its upper extremity to the lay-pitman. This connecting-rod is reciprocated vertically by the up-and-down play of the lay-pitman, and when the crank-shaft is on the downstroke or center this rod pulls downward on the spring, which thereby distends the latter and causes it to pull on the rock-shaft and force the binder arm or finger carried by said protection-rod against the swell, which bears on the shuttle with the desired pressure; but when the crank-shaft approaches the top center, said connecting-rod is raised to release the spring and the swell from the shuttle, which permits the latter to leave its box with ease.

My invention further consists in the peculiar details of construction and arrangement

of parts, as will be hereinafter fully described.

In the accompanying drawings, Figure 1 is a side elevation of my improved shuttle-check, showing the position of the parts when the crank is on the down center. Fig. 2 is a like view with the crank on the top center and 55 the parts in reverse positions. Fig. 3 is a detached view of the parts.

Like numerals of reference denote corresponding parts in all the figures of the drawings, referring to which, 1 designates the 60 crank-shaft; 2, the lay; 3, the pitman intermediate of the lay and crank-shaft; 4, one of the swords on which the lay is carried; 5, the swell of the shuttle-box; and 7, a rock-shaft 65 on which is fixed an arm or finger 8, arranged to impinge against the swell 5. All of these parts are common to the ordinary well-known types of looms, and no novelty thereon is claimed in this application.

To one of the lateral faces of the lay-pitman 3, at an intermediate point of its length, is applied an elongated horizontal bracket 10, which has right-angled feet, through which bolts or other suitable devices are passed to secure the bracket in a fixed position on said 75 pitman. This fixed bracket is provided with a horizontal longitudinal slot 11, through which passes a pivot-bolt 11', on which is pivoted the upper extremity of a vertically-reciprocating rod 12. This rod is made of a single piece of metal—preferably a stout piece of wire—and is bent at an intermediate point of its length to form the straight vertical portion and a laterally-inclined portion, as shown, whereby the inclined upper end of said rod 85 is adapted to be connected in the manner described with the lay-pitman, while its lower straight end is arranged in a fixed guide on the lay-sword to be limited to movement in a vertical plane.

From the arm 8 of the rock-shaft 7 depends a vertical coiled spring 13, the lower extremity of which is near the fixed guide 14 for the lower straight end of the vertically-reciprocating rod. Below the fixed guide the vertically-reciprocating rod is bent into a foot 15

to adapt the same to be readily connected to the spring, and between the extremities of said spring, the arm 8 of the rock-shaft, and the bent foot of the reciprocating rod are arranged wear-strips 16 16', preferably of leather, to take the wear between said parts.

The fixed guide 14 preferably consists of an eyebolt which is suitably fixed to the lay-sword; but I would have it understood that I do not wish to confine myself to this exact form of guide, nor to the connecting wear-straps at the ends of the spring, nor to the exact connection between the reciprocating rod and spring, as I am aware that changes in these and minor other details of construction can be made without departing from the spirit of my invention.

The operation of my invention is obvious. When the crank is on or approaching the down center, as indicated in Fig. 1, the reciprocating-rod is depressed by the lay-pitman, and thus draws down on the coiled spring, which acts to turn the rock-shaft and thus press the binder arm or finger against the swell, which in turn binds on the shuttle. When the crank approaches the top center, (see Fig. 2,) the reciprocating rod is elevated to release the pull of the coiled spring on the rock-shaft, which allows the binder arm or finger to relieve the pressure of the swell on the shuttle, thereby allowing the shuttle to leave its box with an easy motion. This action of the parts eases on the "filling," relieves the pick-motion and picker-staff of strain, and causes less breakage of the warp-threads.

It is obvious that the point of connection between the reciprocating rod and lay-pitman can be varied by moving the pivot-bolt toward or from the crank-shaft, so as to vary the length of reciprocating vertical play or movement of the rod, and thus vary the pressure of the swell on the shuttle.

Having thus described my invention, what I

claim as new, and desire to secure by Letters Patent, is—

1. In a shuttle-check for looms, the combination, with a lay, a crank-shaft, a lay-pitman, a swell, a rock-shaft carrying a binder arm or finger arranged to impinge against the swell, and a spring connected to said rock-shaft, of a vertically-reciprocating rod pivotally connected to the lay-pitman at an intermediate point of its length and at its opposite end to the spring, and a fixed guide on the lay-sword in which said rod is fitted, all arranged and combined for operation in the manner and for the purpose specified. 55

2. The combination, with a lay, a crank-shaft, a lay-pitman, a swell, a rock-shaft carrying a binder arm or finger, and a spring connected to said rock-shaft, of a vertically-reciprocating rod connected at its lower end to said spring, and adjustably connected by means, substantially as described, to the lay-pitman to vary its vertical movement or play, and a guide in which said reciprocating rod is fitted, combined and arranged for operation substantially as and for the purpose described. 70

3. The combination, with a lay, a crank-shaft, a lay-pitman, a swell, a rock-shaft carrying a binder-arm, and a spring connected to the rock-shaft, of a slotted bracket applied laterally to the lay-pitman, a vertically-reciprocating rod connected at its lower end to the spring and having a laterally-bent portion pivoted on a bolt which is adjustably secured in the slotted bracket, and a fixed guide in which the lower straight end of said rod is fitted, substantially as and for the purpose described. 75

In testimony whereof I affix my signature in presence of two witnesses.

NAPOLEON BOISVERT.
